CLAIM

The ornamental design for a boat deck, as shown and described.

DESCRIPTION

FIG. 1 is a perspective view of a boat deck, showing our new design;

FIG. 2 is a top plan view thereof;

FIG. 3 is a side elevational view thereof;

FIG. 4 is a bottom plan view thereof;

FIG. 5 is a front elevational view thereof; and

FIG. 6 is a rear elevational view thereof.

The broken line disclosure of the outline of a boat hull in FIGS. 1 and 3 is for illustrative purposes only.
